United States Patent Office

Des. 226,140
Patented Jan. 23, 1973

226,140

FACE MASK

William R. King, Denver, Colo., assignor to
Sandoz-Wander, Inc., Hanover, N.J.

Continuation-in-part of design application Ser. No.
144,384, May 17, 1971. This application Nov. 19,
1971, Ser. No. 200,640

Term of patent 14 years

Int. Cl. D24—02

U.S. Cl. D83—1

FIG. 1

FIG. 2

FIG. 3

FIG. 4

FIG. 1 is a front elevation view of the face mask, with the side strap in the open position;

FIG. 2 is a bottom plan view of the face mask, with the side strap in the open position;

FIG. 3 is a side elevation view of the face mask, looking to the left in FIG. 1, with the side strap in the open position;

FIG. 4 is an isometric view of the face mask, with the side strap in the closed position.

This is a continuation-in-part of design application Ser. No. D. 144,384, filed May 17, 1971, and now abandoned.

I claim:

The ornamental design for a face mask, as shown.
